UNITED STATES PATENT OFFICE

2,502,950

RESISTOR

Frank R. Hugus and James W. Woelf, Franklin,
Pa., assignors to Joy Manufacturing Company,
Pittsburgh, Pa., a corporation of Pennsylvania

Application May 1, 1948, Serial No. 24,454

12 Claims. (CL 201—58)

1 This invention relates to electrical apparatus, and especially to an electrical resistor.

In some electrical applications, it becomes highly desirable to provide a plurality of electrical resistors which can be quickly and easily installed and which are readily disassembled and assembled without the use of numerous small parts, such as insulating washers and the like, which are apt to be mislaid and lost in the course of maintenance of the resistors. It is also desirable that the resistors be capable of withstanding high temperatures for short time periods without sagging or failing. When the resistors must be disassembled for any purpose, such as maintenance, it is advantageous to be able to take the resistors apart from any vantage point, as for example from either end, from the side or from above the installation.

It is an object of this invention to provide an improved electrical resistor which is quickly and easily installed and which is readily assembled and disassembled. Another object is to provide a resistor which is capable of withstanding high temperatures for short time periods without failure, and which offers a maximum resistance to the effects of corrosion, due to electrolysis, oxidation at elevated temperatures, and the like. These and other objects are accomplished in a resistor made up of a plurality of interlocking parts held together by the terminal clamps at the ends, in which the construction is such as to give the resistor a maximum of physical strength, and the materials are of such a nature as to offer maximum resistance to corrosion.

In the drawings:

Fig. 1 is a top plan view of a resistor made according to the invention.

Fig. 2 is a longitudinal section on the plane of line 2—2 of Fig. 1.

Fig. 3 is a transverse section on the plane of line 3—3 of Fig. 2.

Fig. 4 is a transverse section on the plane of line 4—4 of Fig. 2, and

Fig. 5 is a detailed sectional view of a portion of a resistor showing a modification of one of the parts.

The invention shown is a piece of electrical apparatus comprising a resistor held in place in a pair of supporting frame members 2, having aligned openings 4 therein. End supports 6 of any suitable non-conducting material, such as porcelain or the like, are mounted in opposed relation in aligned openings. Each end support 6 is recessed, as shown at 8, to receive the collapsed ends 10 of a tubular core member 12 which extends

between and is held by the end supports. The collapsed ends 10 present a semicircular cross section, as seen in Fig. 4. For maximum corrosion resistance at high temperatures, the tube 12 is preferably made of stainless steel.

2 A hollow non-conducting member 14 of any suitable insulating material, such as porcelain, is mounted on the core member 12 in such a way as to completely surround or envelop the core member. An electrical conductor 16 is mounted on the hollow non-conducting member; as can be readily seen from the drawings, the conductor 16 is preferably helically wound on the hollow non-conducting member 14. A terminal 18 is bent substantially at right angles, as shown at 20. The bent portion 20 is securely welded to the end of conductor 16 in order to provide a good electrical path between conductor 16 and the terminals. The terminal 18 extends through an opening 22 in its associated end support 6.

A clamping member, indicated generally at 24, is mounted on the terminal at each end of the resistor outside the end support. The clamping member 24 preferably consists of a U-shaped member 26 having aligned openings 28 in the opposite legs of the U. The openings 28 are intended to receive a line conductor (not shown). A screw member 30 threadedly engages the cross member of the U, and is adapted to clamp the terminal 18 between the line conductor and the end of the screw.

When the clamping members 24 are thus engaged in tightly clamping the terminals 18, the U-shaped members 26 tightly engage at their inner ends the outer faces of the end supports 6, and hold the parts of the resistor together in an assembled relation between them. In order that the U-shaped member 26 may not readily slip off its associated terminal 18, each terminal 18 is preferably provided with a slightly wider portion beyond the end of the member 26. Thus the terminal 18 will be T-shaped, as seen in Fig. 1, with the cross of the T being only slightly wider than the upright of the T.

To each terminal 18 there is secured, as by welding, an inwardly extending projection 32. Integral with the projection 32 are provided cooperating extensions 34 and 36 substantially at right angles to the projection 32. The extensions 34 and 36 are adapted to grip and hold between them a lock member 38. Member 38 is cylindrical as seen in Fig. 4 to lie in the semi-circular cross section of the collapsed end 10 of core 12, and is flat at 39 to cooperate with the flat extension 32. The lock member 38 cooperates with the collapsed

end of the core member 12 in non-rotative relationship thereto by means of an interlocking protuberance and recess. In the embodiment shown, the protuberance 40 consists of a boss on the lock member 38, and the recess 42 is provided in the walls of the collapsed end 10 of the core member 12. The protuberance and recess serve to hold the member 38 and core 12 together, against both axial and angular relative displacement.

It will be appreciated by those skilled in the art that the lock member 38 may be made of any satisfactory non-conducting material such as porcelain, or the like.

In order to avoid the corrosion resulting from electrolytic action of dissimilar materials, in contact, the projections 32, terminals 18, and conductor 16 are preferably all made of the same metal or alloy.

Fig. 5 shows a modified structure for locking the resistor in assembled relation. In this figure, the lock member 538 is provided with a slot 539 to receive a single extension 536 on the projection 532; otherwise, the structure is substantially the same as shown in the other embodiments.

Operation

In assembling a resistor made according to the invention, each lock member 38 is put in place in a collapsed end of the tubular core member 12 with the protuberance or boss 40 engaging its cooperating recess 42. A projection 32 is slipped in place on the flat portion 39 of each lock member in such a manner that the extensions 34 and 36 engage the ends of the lock member. These parts are then slipped into a hollow non-conducting member 14; a conductor 16 is slipped over the outside of member 14, and terminals 18 are securely welded to the projections 32; thus securely locking the parts together. The bent portion 20 of each terminal is thereupon welded to the adjacent end of the conductor 16.

The resulting unitary construction is put in place in its installation with the terminals 18 extending outward through aligned openings 4 in the supporting frame members 2. The end supports 6 are put in place in the openings 4, with the collapsed ends 10 received in the recesses 8 and the terminals 18 extending through the openings 22. Clamping members 24 are put in place over the ends of terminals 18.

The line conductor ends are then slipped through the aligned openings 28 in the U-shaped piece 26, and the screw 30 is turned so as to clamp the terminal 18 between the conductor and the screw end. The resistor is then held together by the clamping and restraining action of the clamping members 24 at its ends, operating against the outer faces of the end supports 6. If it is desired to take the resistor apart, it is merely necessary to remove the clamping members 24 from the line conductors, after which the entire resistor is easily taken apart from either end by lifting the clamping member 24 off its associated terminal 18, pulling the end support 6 outward endwise, and then pulling the body of the resistor consisting of the core member 12, hollow member 14, conductor 16, and lock members 38 out through the opening 4 in the frame member 2.

If there is not room outside the frame members 2 to remove the resistor body endwise, it can be removed from a position between the frame members 2, as, for example, from above, simply by removing the end supports 6 as set

forth heretofore, and by thereafter moving the resistor body endwise through one of the openings 4 just enough to permit the opposite terminal 18 to clear the frame member 2.

The advantages of a resistor made according to this invention will be evident to one skilled in the art, and consist in ease of construction of the unitary resistor body, in the ease with which this resistor body may be installed in its supporting frame members, and the corresponding ease with which it may be removed therefrom for maintenance or other purposes; and the high degree of physical strength of the structure and the resistance to corrosion and the like.

While there is in this application specifically described one form which the invention may assume in practice, it will be understood that this form of the same is shown for purposes of illustration, and that the invention may be modified and embodied in various other forms without departing from its spirit or the scope of the appended claims.

What we claim as new and desire to secure by Letters Patent is:

1. A resistor comprising a pair of non-conducting end supports, a core member extending between and held by the end supports, a hollow non-conducting member enveloping and supported by the core, an electrical conductor supported on the hollow non-conducting member, terminals in electrical contact with the conductor ends and extending through the end supports, and clamping members mounted on the terminals outside the end supports, each clamping member including means to clamp its associated terminal between an electrical line conductor and a portion of the clamping member.

2. The resistor set forth in claim 1, in which each clamping member is U-shaped and has aligned openings in the legs of the U to receive the electrical conductor.

3. A resistor comprising a pair of non-conducting end supports, a core member extending between and held by the end supports, a hollow non-conducting member enveloping and supported by the core, an electrical conductor supported on the hollow non-conducting member, terminals in electrical contact with the conductor ends and extending through the end supports, a projection on each terminal and extending inward toward the opposite terminal, a lock member between each projection and the core end to hold the core and hollow member in assembled relation, means cooperating with the terminals, the end supports, and with the conductors of an electric circuit to hold the resistor parts together.

4. A resistor comprising a pair of non-conducting end supports, a core member extending between and held by the end supports, a hollow non-conducting member enveloping and supported by the core, an electrical conductor supported on the hollow non-conducting member, terminals in electrical contact with the conductor ends and extending through the end supports, a projection on each terminal and extending inward toward the opposite terminal, a lock member between each projection and the core end to hold the core and hollow member in assembled relation, and clamping members mounted on the terminals outside the end supports, each clamping member including means to clamp its associated terminal between an electrical line conductor and a portion of the clamping member.

5. Electrical apparatus comprising, a pair of

supporting frame members having aligned openings, a non-conducting end support in each opening, a core member extending between and held by a pair of said end supports, a hollow non-conducting member surrounding and supported by the core, an electrical conductor supported on the hollow non-conducting member, terminals in electrical contact with the conductor ends and extending through the end supports, and clamping members mounted on the terminals outside the end supports, each clamping member including means to clamp its associated terminal between an electrical line conductor and a portion of the clamping member.

6. The apparatus set forth in claim 5, in which each clamping member is U-shaped and has aligned openings in the legs of the U to receive the electrical line conductor.

7. Electrical apparatus comprising a pair of supporting frame members having aligned openings, a non-conducting end support in each opening, a core member extending between and held by a pair of said end supports, a hollow non-conducting member surrounding and supported by the core, an electrical conductor supported on the hollow non-conducting member, terminals in electrical contact with the conductor ends and extending through the end supports, a projection on each terminal and extending inward toward the opposite terminal, a lock member between each projection and the core end to hold the core and hollow member in assembled relation, and means cooperating with the terminals, the end supports, and with the conductors of an electric circuit to hold the resistor parts together.

8. The apparatus set forth in claim 7, in which the core member is a tube with collapsed ends, and the lock member at each end lies between the collapsed end and the projection.

9. The apparatus set forth in claim 8, in which the lock member and the core are provided with an interlocking protuberance and recess.

10. Electrical apparatus comprising a pair of

supporting frame members having aligned openings, a non-conducting end support in each opening, the support having a recess in its inward face, a tubular core member having collapsed ends received in the recesses of a pair of opposed aforesaid end supports, a hollow non-conducting member on the core member, an electrical conductor supported on the hollow non-conducting member, a terminal in electrical contact with each conductor end and extending through its adjacent end support, and means cooperating with the terminals, the end supports, and with the conductors of an electric circuit to hold the resistor parts together.

15 11. In the apparatus set forth in claim 10, an inwardly extending projection associated with each terminal, and a lock member between the projection and the core end.

12. The apparatus set forth in claim 11, in which the lock member and the core member are provided with an interlocking protuberance and recess.
